UNITED STATES PATENT OFFICE.

EDWARD POSSON, OF CHICAGO, ILLINOIS.

BRAKE-HANGER MECHANISM.

1,364,642.

Specification of Letters Patent.

Patented Jan. 4, 1921.

Original application filed March 17, 1917, Serial No. 155,415. Divided and this application filed October 16, 1917. Serial No. 196,831.

To all whom it may concern:

Be it known that I, EDWARD POSSON, a citizen of the United States, residing at Chicago, in the county of Cook and State of Illinois, have invented certain new and useful Improvements in Brake-Hanger Mechanism, of which the following is a specification.

This invention relates to brake-hanger mechanism, and the present application is a division of my prior application, Serial No. 155,415, filed March 17, 1917.

The principal object of the invention is to provide improved means for hanging and mounting the brake-shoes on the truck of a railway car, and in particular to provide a form of construction which may be used efficiently in connection with the clasp brake described in my prior application, above referred to. Another important object is to provide brake-hanger mechanism which will occupy the minimum amount of space and permit the convenient use of the invention in connection with modern passenger car trucks, for instance, in which the space for the brake-beams and brake-shoes between the ends of the truck is extremely limited. Still another feature is to provide means for pivotally supporting the brake-beams on the hangers in combination with means for maintaining the brake-shoes in the proper operative positions with respect to the brake-beams. Another object is to provide means for securely holding the brake-hangers and brake-shoes on the brake-beams while permitting the ready removal thereof when desired. A further feature is the provision of means for resiliently supporting the lower parts of the brake-shoes to prevent the swinging thereof away from the peripheries of the car wheels. Other objects relate to various features of construction and arrangement which will appear more clearly hereinafter.

The nature of the invention will be understood from the following specification taken in connection with the accompanying drawings, in which one embodiment of the invention is illustrated.

In the drawings—

Figure 1 shows an enlarged side elevation of a portion of a car truck illustrating the application of my invention thereto;

Fig. 2 shows a vertical section through a

brake-hanger illustrating the connection of 55 the brake-shoe with the brake-beam;

Fig. 3 shows a perspective view of a brake-hanger bracket;

Fig. 4 shows a perspective view of the 60 brake-head adjusting connector;

Fig. 5 shows a perspective view of the 65 brake-head adjusting spring and bracket;

Fig. 6 shows a side elevation of a portion 70 of a brake-beam;

Fig. 7 shows an end elevation thereof; 75

Fig. 8 shows a top plan view of a portion 80 of the brake-beam;

Fig. 9 shows a perspective view of one of 85 the brake-hangers, and

Fig. 10 shows a perspective view of a 90 95 brake-beam key.

In the drawings, the invention is illustrated as applied to a car truck designated generally by the numeral 10 and having a wooden frame. This truck comprises the 75 side frame members 11, upon which are mounted the lever-carrying brackets 12 located above the axles 13 of the car wheels 14. These brackets serve to support the 80 brake mechanism which comprises one or 85 more suspending links 15 pivotally connected to the brackets 12 by means of bolts 16, and pivotally connected at their lower ends to the lever carrier 17 by means of pins 18. The lever carrier 17 is pivotally connected 85 at the point 19 to a truck lever 20, the upper end of which is pivotally connected to a 90 brake-rod 21. The side frames of the truck have projecting downwardly therefrom the arms 22, which are connected by pins 23 95 with the spring plank hangers or brackets 24. These brackets carry shoes 24^a upon which the spring-planks 25 are mounted. The springs 26 are mounted on the spring-plank 25 according to the modern method of 95 car construction. The foregoing features are described more fully in my prior application, above referred to, and are illustrated here for the purpose of showing the application of the particular invention to which the 100 present application is confined. It will be understood that my improved brake-hanger mechanism may be used in connection with various forms of car trucks or brake operating devices.

At each side of the car a hanger bracket 30 is secured to the transverse frame members 31 of the car truck by means of bolts

32, and in the instance shown in Fig. 1, the bracket is directed downwardly, the parallel ears 31^a at the lower end thereof being apertured and pivotally connected to the 5 brake-hanger 33, illustrated particularly in Fig. 9. The lower end of the brake-hanger 33 is provided with a cylindrical bearing portion 34 adapted to be rotatably engaged by the cylindrical part 35 of the brake-beam 10 36. The central part of the brake-beam has a rectangular cross-section, as illustrated particularly in Figs. 6, 7, and 8, and each brake-beam carries at its opposite ends a cylindrical part 35, which terminates in a 15 part 37 of reduced diameter having an annular groove 38 formed therein adjacent its extremity. The part 34 of the brake-hanger 20 rotatably engages the part 35 of the brake-beam, and thus a free movement of the 25 brake-beam toward or away from the car wheel is permitted, and this movement is effected through the brake-lever mechanism, 30 previously described. Each truck lever 20 is connected to the adjacent brake-beam 36 by means of a truck lever connector 40 having an enlarged bearing member 40^a at one end thereof mounted on the cylindrical portion 35 of the brake-beam, and having apertures 40^b at the other end, by means of 35 which a pivotal connection is made with the truck lever 20. By providing a plurality of apertures 40^b, it is possible to change the connection on the truck levers in order to vary the position and the path of travel of the 40 brake-shoe and brake-beam. The part 35 of the brake-beam is provided with a keyway 35^a, which permits a rigid connection with the member 40, and this keyway also serves to permit the formation of a fixed 45 connection between the brake-beam and the bracket 41, which is mounted on the part 35 and which carries the brake-head adjusting spring 42. This spring is mounted between the downwardly directed ears 41^a of the 50 bracket and is secured thereto by means of rivets 43. The brake-head 45, carrying the brake-shoe 46, is rotatably mounted on the reduced end portion 37 of the brake-beam and abuts against the shoulder 37^a formed 55 by the end of the part 35. The brake-head is maintained on the brake-beam by means of a brake-beam key 47 having the form illustrated particularly in Fig. 10. This key has a U-shaped slot 47^a, the walls of which are 60 adapted to fit into the annular groove 38, formed in the end of the brake-beam. The key is further provided with an upward extension 47^b having an aperture 47^c therein, by means of which the key is secured to the 65 flange 45^a of the brake-head by means of the pin 48. In this way, the brake-head is securely fixed on the end of the brake-beam without the use of nuts or other similar fastening devices, and the brake-shoes are maintained in the proper positions on the brake- 70 beams by means of the spring 42, previously described, which is bent at its lower end to form the apertured ears 42^a, by means of which a pivotal connection is formed with the connecting member 49, having the form 75 shown particularly in Fig. 4. This connecting member is pivotally connected at its other end to the flange 45^a of the brake-head by means of a pin 50. This connecting device serves to maintain the lower end of the 80 brake-shoe in contact with the car wheel when the brake-shoes are moved into operative positions, and at the same time the spring 42 permits the necessary adjustment of the brake-shoe to the periphery of the car 85 wheel. It will be apparent that by means of this simple construction, the brake-hanger mechanism is mounted on the truck while occupying only a limited space, and at the same time the necessary free movement of the 90 brake-beam is permitted.

Although I have shown and described a particular embodiment of the invention for purposes of illustration, it may be understood that it may be constructed in various 95 other forms without departing from the spirit of the invention as defined in the appended claims.

What I claim is:

1. In a railway car, a car truck, a brake beam suspended from said truck, a brake shoe pivotally mounted on said brake beam, a flat spring fixed on said brake beam and extending radially therefrom, and means for connecting said spring to said brake shoe. 100
2. In a railway car, a car truck, a brake beam carried by said truck, a brake shoe pivotally mounted on said brake beam, a resilient member non-rotatively mounted on said brake beam at one side of said brake shoe and extending radially from said brake beam, and means connecting said member to said brake shoe. 105
3. In a railway car, a car truck, a brake beam carried by said truck, a brake shoe pivotally mounted on the end of said brake beam, the end of said brake beam being provided with an annular groove, a locking plate secured to said shoe and engaging said annular groove, and means for maintaining said brake shoe in proper position with respect to a wheel of said truck. 110
4. In a railway car, a car truck, a brake-hanger suspended from said truck, a brake-beam having a cylindrical portion rotatably 115 engaging said brake-hanger, brake operating mechanism comprising a member non-rotatably mounted on said cylindrical portion, a brake-shoe pivotally mounted on said cylindrical portion, and means non-rotatably engaging said cylindrical portion and connected to said brake-shoe for maintaining the latter in proper position with respect to a wheel of said truck. 120
5. In a railway car, a car truck, a brake- 125

beam suspended from the frame of said truck, means for moving said brake-beam toward and away from a wheel of said truck, a brake-shoe pivotally mounted on 5 said brake-beam, a bracket member fixed on said brake-beam adjacent said shoe, a spring member secured to said bracket member and extending downwardly therefrom, and means 10 pivotally connecting the lower ends of said spring member with the lower part of said brake-shoe.

6. In a railway car, a car truck, a brake-

beam suspended from said truck, brake operating mechanism comprising a member non-rotatably mounted on said brake-beam 15 adjacent said brake-hanger, a brake-shoe mounted adjacent the end of said brake-beam, said brake-beam having an annular groove in the end thereof, and a key engaging said groove. 20

In testimony whereof, I have subscribed my name.

EDWARD POSSON.
